UNITED STATES PATENT OFFICE.

ALFORD B. HENSON, OF FRANKLIN, KENTUCKY.

DEMOUNTABLE RIM.

1,301,695.

Specification of Letters Patent. Patented Apr. 22, 1919.

Application filed April 13, 1917. Serial No. 161,844.

To all whom it may concern:

Be it known that I, ALFORD B. HENSON, a citizen of the United States, residing at Franklin, in the county of Simpson and State of Kentucky, have invented new and useful Improvements in Demountable Rims, of which the following is a specification.

This invention relates to wheels and especially to wheels having pneumatic tires.

10 The objects of the invention are to simplify and improve the construction, arrangement and combination of parts entering into the make-up of the device.

With these and other ends in view which 15 will readily appear as the nature of the invention is better understood, the same consists in the improved construction and novel arrangement and combination of parts which will be hereinafter fully described and particularly pointed out in the claims.

20 In the accompanying drawings has been illustrated a simple and preferred form of the invention, it being, however, understood that no limitation is necessarily made to the 25 precise structural details therein exhibited, but that changes, alterations and modifications within the scope of the claims may be resorted to when desired.

In the drawings:

30 Fig. 1 is a side elevation of a wheel constructed in accordance with the invention.

Fig. 2 is a sectional detail view taken on the line 2—2 in Fig. 1.

35 Fig. 3 is a sectional detail view taken on the line 3—3 in Fig. 2.

Fig. 4 is a sectional detail view taken on the line 4—4 in Fig. 1.

Fig. 5 is a plan view of a portion of the rim without the tire.

40 Fig. 6 is a perspective detail view showing a portion of the demountable rim, the parts of the same being shown separated.

Fig. 7 is a perspective detail view of the valve receiving portion of the rim.

45 Fig. 8 is a perspective detail view of a portion of the expansion ring.

Fig. 9 is a perspective detail view of the locking dog cooperating with the expansion ring.

50 Fig. 10 is a perspective view of a wrench or tool specially constructed to operate in connection with the invention.

Corresponding parts in the several figures of the drawings are denoted by like characters of reference.

55 The felly 15 of the improved wheel is re-

inforced by facing plates 16, 17, which are mounted respectively on the back and front faces, the back plate 16 having a flange 18 that forms an abutment for the rim. The 60 latter, which is generally designated by R, is split so as to form two annular members, viz., the back member 19 and the front member 20, the latter being partly seated in a recess 21 formed in the external face of the 65 back member 19. The members 19 and 20 have been shown as being provided with clencher flanges 22 adapted to clench the tire 23, but other means of connecting the tire with the rim may be used without departing 70 from the invention.

The member 19 is of a width almost equal to the width of the felly 15, and said member 19 is provided on its inner face with a series of transversely disposed lugs or cleats 75 24 adapted to be seated on the outer face of the felly and serving to space the member 19 from the felly. Each of the lugs 24 is provided with a groove 25. The felly 15 is provided with a transverse annular groove 80 26 wherein is seated a ring 27, said ring being assembled with the felly by the facing plate 17, the latter and the back facing plate 16 being secured on the felly by transverse bolts 28. Each of said bolts is provided with an 85 anti-friction roller 29, see Fig. 2, said anti-friction rollers supporting the ring 27 and facilitating the operation thereof. The ring 27 is provided at a convenient point with a series of inwardly extending rack teeth 30 and adjacent to said teeth with a series of inwardly extending ratchet teeth 31. Pivotally supported in a recess 32 of the felly, on a bolt or pivot member 33, is a dog 34 having teeth 35 that engage the ratchet teeth 31. 90 Said dog is also provided with an arm or extension 36 lying in the path of a transverse opening 37 in the felly, there being provided a suitable pivoted or sliding cover 38 by means of which the outer end of said 95 opening may be closed. Said opening is for the admission of a portion of a peculiarly constructed wrench W best seen in Fig. 10, said wrench consisting of a handle 39 having a head 40 on which is mounted a 100 pinion 41 and a spindle 42 which is axially disposed with respect to the pinion, said spindle having a tapering or conical end portion 43. When the spindle is inserted into the opening 37, the tapered end thereof 105 will engage the arm 36 of the dog, depressing the latter against the tension of a spring 110

44 whereby its toothed portion 35 is normally held in engagement with the ratchet teeth 31 of the ring 27. By further inserting the spindle within the opening 37, the 5 pinion 41 will be presently placed in mesh with the rack teeth 30 of the ring, and by turning the handle 39 the said ring may now be turned about its axis which is coincident with the axis of the wheel. When the 10 wrench is withdrawn, the toothed portion of the dog is restored to engagement with the ratchet teeth 31 and the ring 27 will thus be secured against further rotation due to any reason that is likely to occur.

15 The member 19 of the rim is provided with bayonet slots 46 and the member 20 is provided with lugs or projections 47 adapted for engagement with said bayonet slots, said lugs 47 being of such length as to extend 20 beyond the inner face of the member 19 when the parts are assembled. The bayonet slots 46 are formed closely adjacent to the transversely disposed lugs or cleats 24 heretofore described. The member 20, in addition to 25 the lugs 47, is provided with a special lug 48 which, when the parts are assembled, is positioned adjacent to the toothed portion of the ring 27, near the juncture of the rack teeth and the ratchet teeth. The head 40 of 30 the wrench W is provided with a stud 49 adapted for engagement with the lug 48. The ring 27 is provided with a plurality of obliquely disposed cam members 50, as best seen in Figs. 5 and 8, there being one such 35 cam member for each of the lugs or cleats 24, and said cam members being arranged to ride in the notches 25 of said cleats, and also to engage the lugs 47 of the member 20 when the parts are being assembled.

40 The member 19 of the rim may be permitted to remain permanently on the felly although, of course, it may be detached whenever desired. Assuming said member to be in position on the felly and the tire 45 having been placed in position thereon, the tire will be secured by the member 20 by pushing the latter into position in the recess 21 of the member 19, it being evident that it must first be adjusted to a position where the 50 lugs 47 will enter the portions of the bayonet slots that are transversely disposed with respect to the felly and also that the lug 48 must be properly positioned adjacent to the opening or socket 37. The member 20 having 55 been pushed into position until the lugs 47 are positioned in advance of the cam members 50 of the ring 27, it next becomes necessary to turn the ring 27 so as to move the lugs 47 into the angles of the bayonet 60 slots in alinement with the portions of said slots that are positioned longitudinally with respect to the felly. This is accomplished by first inserting the spindle and pinion portion of the wrench into the socket 37 thereby 65 unlocking the dog 34. Now, by turning the wrench, the ring 27 will be rotated about its axis causing the cam members 50 to engage the portions of the lugs 47 that project beyond the inner face of the rim, thereby forcing said lugs into the angles of the bayonet slots. By continued rotation of the wrench the stud 49 will engage the lug 48, thereby turning the member 20 about its axis, and placing the lugs 47 within the longitudinal portions of the bayonet slots 46, thereby locking the members of the rim together and at the same time and by the same operation clenching the tire securely in position. Removal of the wrench from the socket 37 causes the ring 27 to be locked in 80 position by the dog 34. The parts may be disassembled by reversing the mode of operation.

15 The member 19 of the rim is provided at a point which is preferably diametrically 85 opposite to the socket 37 with a recess 53 into the inner end of which extends the valve nipple 54 of the inner tube 55 of the tire. The valve nipple is threaded for the reception of the specially constructed valve 90 fixture 56 which extends laterally in an outward direction between the felly and the rim, the felly being provided with a recess 57 for the accommodation thereof. The fixture 56 has an angular duct 58 and the outer 95 end thereof is capped at 59. The fixture thus constructed permits the tire to be removed much more readily than if it were extended in the customary manner, radially through the tire.

100 From the foregoing description, taken in connection with the drawings hereto annexed, the operation and advantages of this invention will be readily understood. The construction is simple, of such a nature as to 105 permit the parts to be assembled with the greatest possible facility, and it has been found to be in every respect thoroughly useful for the purposes for which it is provided.

110 Having thus described the invention, what is claimed as new is:

1. In combination with a wheel having the periphery of its felly provided with a circumferential recess, a demountable tire carrying rim, transversely extending cleats on the inner periphery of said rim bearing upon said felly, said cleats being provided with transverse notches, a ring circumferentially movable within said recess, lugs extending diagonally across the outer periphery of said ring and engageable within said notches, means for moving said ring circumferentially to dispose said lugs within said notches, ratchet teeth formed on the inner periphery of said ring and a bar pivoted within a recess in said felly and provided with teeth engageable with said ratchet teeth whereby said ring may be held in adjusted position.

2. A wheel having the periphery of its felly provided with a circumferential recess, a demountable tire carrying rim associated with said felly, transverse cleats on the inner periphery of said rim bearing upon the periphery of said felly and provided with transverse notches, a circumferentially movable ring disposed within said recess, inclined lugs on the outer periphery of said ring disposed within said notches, a plurality of rack teeth formed on the inner periphery of said ring, a plurality of ratchet teeth formed on the inner periphery of said
- ring adjacent said rack teeth, a bar pivoted within a recess in said felly and provided with teeth normally engaging said ratchet teeth, the end of said bar adjacent said rack teeth being provided with a curved recess, said curved recess and said rack teeth being adapted for the engagement of means for moving said ring circumferentially, engagement of said means within said curved recess moving said bar out of engagement with said rack teeth.

In testimony whereof I affix my signature. 25
ALFORD B. HENSON.
